UNITED STATES PATENT OFFICE.

CLARENCE E. HEATON, OF CHICAGO, ILLINOIS, ASSIGNOR TO WILSON BROTHERS, OF CHICAGO, ILLINOIS, A CORPORATION.

DISPLAY BOX.

Application filed November 7, 1921. Serial No. 513,253.

To all whom it may concern:

Be it known that I, CLARENCE E. HEATON, a citizen of the United States, residing in Chicago, county of Cook, and State of Illinois, have invented certain new and useful Improvements in Display Boxes, of which I do declare the following to be a full and exact description, reference being had to the accompanying drawing, forming a part 10 of this specification.

Fig. 1 is a perspective view of a display box embodying my invention.

Fig. 2 is a view in elevation showing my invention in slightly modified form.

15 The present invention has for its object to provide an improved construction of box or container for such articles as men's garters, whereby the articles may be attractively displayed upon store counters or in like 20 situations. The invention consists in the features of novelty hereinafter described, illustrated in the accompanying drawing and particularly pointed out in the claims at the end of this specification.

25 In the drawing, A designates the body of the box that may be of convenient size and shape to receive a number of individual boxes B, each adapted to hold a single pair of garters. C designates the cover of the 30 box that may be hinged to the body A at one side, a suitable form of stop device D being employed to limit the movement of the cover C and hold the same in approximately vertical position.

35 The cover C of the box is formed with an opening c, across which one of the garters E to be displayed will be held in extended position. At each side of the opening c are formed slots c' through which the band or 40 webbing e of the garter E will be passed, these slots c' being diagonally disposed as shown in the drawing. In the preferred embodiment of the invention, the diagonal slots c' formed in the cover C are connected 45 with the opening c by means of the slots c'', these slots c'' permitting the garter E to be more readily inserted into the slots c'.

50 Subjacent the bottom of the opening c is formed a hole c''' that extends through the cover C. The purpose of this hole c''' is to permit the button e' of the garter E to be passed therethrough from one side of the cover C, so that the head of the button e' after it has been passed through the hole c''' 55 may be engaged by the button loop e'' of

the garter E. The button e' and the button loop e'' are suspended from the apex of the garter E, the button e' being carried by a button tab e'', and the button loop e'' being suspended from a loop formed in the fabric 60 e''' that is stitched across the front of the garter E in a manner well understood by those familiar with men's garters of this type.

65 In arranging a garter E upon the cover of the box C (when the cover C is provided with slots c' and c''), the band e of the garter will be passed through the slots c'' and into the slots c' in the position shown in Fig. 1 of the drawing, the cast-off loop e''' being 70 at such time engaged with a stud e'' in the usual manner. The button e' will be passed through the hole c''' in the cover C, after which the button loop e'' will be slipped over the button e' until the button and loop are 75 in the relative position shown in the drawing. When the garter E is thus arranged upon the cover C, the garter will be held in distended position so as to effectively display it without any undue strain upon the 80 parts, and in a position approximating that which the garter would have in use upon a wearer's leg. When thus in position upon the cover C of the box, the garter is most effectively and attractively displayed.

85 Garters of the type illustrated in the drawing are frequently formed of a single band of wide elastic webbing, the ends of which are cut diagonally and connected at the front of the garter, at which point the 90 sock-engaging button and loop are arranged. For garters thus formed of a continuous band (i. e. without a cast-off loop and stud), it is particularly desirable to provide the slots c'' connecting the opening c 95 with the diagonal slots c'; and even when the garters are formed with cast-off loops and studs, I prefer to employ the connecting slots c'', as these slots enable the garters to be more readily placed in position upon the cover C. By reference to Fig. 2 of the drawing, it will be seen, however, that the slots c'' are not necessary when the garter E is provided with a cast-off loop and stud e''' and e'', since with such type of garter 100 the band e of the garter can be readily threaded through the diagonal slots c'.

105 The portions of the cover between the diagonal slots c' and the opening c constitute supports for the body portion of the 110

garter and the portion of the cover C between the hole c^s and the opening c form a support for the sock-engaging members of the garter. While I prefer to form the several supports in the manner above described, said supports may be otherwise formed to display the garter in extended position without departing from the broad scope of the invention.

10 So far as I am aware my invention presents the first instance of a display box having a cover or part provided with oppositely disposed, diagonal supports for the body of a garter and with an adjacent support for the sock-engaging member of the garter, whereby the garter may be displayed without undue strain in approximately the position assumed by such parts when in use upon a wearer's leg.

20 Having thus described my invention, what I claim as new and desire to secure by Letters Patent is:—

1. Means for displaying garters comprising a flat part having in its upper portion 25 slots placed at a distance apart through which slots the leg band of the garter may

pass and having at a distance below said slots a hole to admit the button of the garter tab, and having also a relatively large opening above said hole and between said slots, 30 through which opening the body of the garter may be exposed and through which the button loop of the garter may be passed to enable said loop to engage said button.

2. A display box of the character described 35 having a part formed with an opening therein and having slots at opposite sides of said opening to admit the leg band of the garter and having also slots extending between said first mentioned slots and said opening to permit the leg band to be passed therethrough and having below the bottom of said opening a hole to receive the sock-engaging member of the garter, to hold the garter in distended position. 40

3. A display box of the character described, having a cover formed with an opening therein, and having diagonally arranged slots at opposite sides of said opening and having slots connecting said diagonally arranged slots with said opening. 45

CLARENCE E. HEATON.
